United States Patent Office.

ROBERT ENGELS, OF PHILADELPHIA, PENNSYLVANIA.

Letters Patent No. 101,598, dated April 5, 1870.

IMPROVEMENT IN TICKET-PUNCH.

The Schedule referred to in these Letters Patent and making part of the same.

To all whom it may concern:

Be it known that I, ROBERT ENGELS, of Philadelphia, Pennsylvania, have invented an improved Ticket-Punch, and I do hereby declare the following to be a full, clear, and exact description of the same.

My invention consists of a ticket-punch, in which the spring for operating the jaws is arranged between the operating portions of the said jaws, instead of between the handles, as usual. And my invention also consists in a case or box attached to one of the jaws, in place of the usual stripper-plate, and adapted for the reception of the said spring, and of a portion of the other jaw, all of which will be fully described hereafter.

In order to enable others to make and apply my invention I will now proceed to describe the mode of constructing and using the same, reference being had to the accompanying drawing which forms a part of this specification, and in which—

Figures 1 and 2, are views of the two main portions of my improved ticket-punch, detached from each other.

Fig. 3, a sectional view of the complete punch.

Fig. 4, a transverse section on the line 1, 2, fig. 3, looking in the direction of the arrow, and

Fig. 5, a view of a modification.

Similar letters refer to similar parts throughout the several views.

The jaws A and A' of the punch are crossed and connected together by a pin a, and have the usual handles b b which can be plain, as shown in the first three figures of the drawing, or one of them can be formed into a loop, as seen in fig. 5, for convenience of attachment to a cord or light chain.

A thin metal box or case, B, is secured to the jaw A by screws, c c c, in such a position that space D shall intervene between it and the end, f, of the said jaw, and within this case is contained the end, f', of the jaw A' to which the punching tooth, h, is secured, the latter being arranged to pass through a hole, i, of the case, and into the opening h' of the jaw A, when the handles, b b, are pushed toward each other, but

remaining entirely within the case, as shown in fig. 2, when the pressure is removed, owing to the action of a spring, m.

The latter is a simple strip of bent steel contained within the case B, and arranged to bear against the end of the jaw A', it being held within a notch, p, of the jaw A', and thus maintained in a proper position.

The spring is designed to take the place of the usual inconvenient "back-spring," which is placed between the handles of the punch in the manner indicated by dotted lines in fig. 3, this "back-spring" interfering with the proper manipulation of the handles and becoming frequently broken, owing to its exposed position.

The spring m, moreover, is fully protected by the case B, and is placed in a more advantageous position, acts more directly, is less expensive, and more readily replaced when broken, than the "back-spring."

The case B besides serving as a guard for the spring, takes the place of the usual stripper-plate, gives the instrument a neat appearance, and covers all angular or projecting portions of the instrument, which would be likely to catch in or tear the pocket.

I claim as my invention and desire to secure by letters patent—

1. The spring m, attached to the jaw A of a ticket-punch, contained within a case B of the same, and arranged to bear against the jaw A' of the said punch, substantially, in the manner described.

2. The case B secured to the jaw A so as to be readily detached therefrom, and in such a position that it shall serve as a stripper-plate for the punch, substantially as specified.

3. The case B adapted for application to a punch, substantially as herein set forth.

In testimony whereof I have signed my name to this specification in the presence of two subscribing witnesses.

ROBERT ENGELS.
